CAR TRUCK

Charles R. Busch, Orange, N. J., assignor to Buffalo Brake Beam Company, New York, N. Y., a corporation of New York

Application November 1, 1939, Serial No. 302,267

23 Claims. (Cl. 188—212)

This invention relates to car trucks embodying improvements over the car trucks and side frames disclosed and covered by my U. S. Letters Patent Nos. 2,170,112 and 2,170,123, dated August 22, 1939. In said patents the side frames of a car truck are disclosed as having guiding means upon and along the side frames for guiding the brake beam at a suitable angle of inclination during the operation of the brake, such guiding means including two spaced apart guide flanges or ledges on the side frames, the upper guide flange being disclosed as formed in one piece with the side frame, so that to remove the brake beam from the truck it was moved backwardly along the guides and then removed from the guides at points above the spring seats, as the lower guide flanges or ledges extended from or merged with the spring seat, so that the beam could not be removed downwardly below the spring seats.

It has been found desirable to remove the brake beam upwardly between the side frames, that is, upwardly from the supporting and guiding flanges below the brake beam, and to this end one object of the present invention is to form the upper flanges or ledges, which confine the brake beam, as members or pieces formed or cast independently of the side frames and to so mount them that they can be taken off from the side frames or can be mounted so as to have a movement sufficient to allow the brake beam to be raised and removed.

Other objects of the invention are to improve car trucks and their side frames generally so as to be more satisfactory to the railways using such trucks, and an object which is obtained incidental to the present improvements is that the truck is made more or less universal in that not only may the brake beam be guided along the side frames during brake operation, but also, when the separate upper flanges of the guiding means are detached from the side frames, the brake beam may be mounted so as to swing from hangers supported on the side frames, such swinging movements not supporting the beam on the remaining lower flanges, which then serve to catch the ends of the beam in case of failure of its hanger supports, so that they will prevent the beam from falling to the track.

These being among the preferred objects of the present invention, the same consists of certain features of construction and combinations of parts to be hereinafter described and then claimed with reference to the accompanying

drawings illustrating certain embodiments of the invention and wherein

Fig. 1 is a broken side elevation of so much of a tension member and guide column of a side frame as is necessary to illustrate the present improvements;

Fig. 2 is a section on the line 2—2, Fig. 1, showing how the separate upper flange is detachably supported;

Fig. 3 is a section on the line 3—3, Fig. 1, at points below the section in Fig. 2;

Fig. 4 is a transverse section on the line 4—4, Fig. 1;

Fig. 5 is a perspective view of the removable beam confining flange;

Fig. 6 is a perspective view of the wear plate for taking the friction of the ends of the beam;

Fig. 7 is a broken side elevation similar to Fig. 1, but illustrating a modification of the invention;

Fig. 8 is a section on the line 8—8, Fig. 7;

Fig. 9 is a section on the line 9—9, Fig. 7;

Fig. 10 is a transverse section on line 10—10, Fig. 7;

Fig. 11 is a perspective view of a modified wear plate;

Fig. 12 a section on line 12—12, Fig. 7; and

Fig. 13 is a sectional view showing the beam confining flange entirely removed from the side frame, to enable the beam to be supported by hangers and to drop upon the supporting flange in case of failure thereof.

Referring to Figs. 1 to 4 inclusive they will readily be understood by those skilled in the art, particularly on considering the aforesaid patents, and there is shown only enough of a side frame including a tension member and a guide column to indicate the position of the present improvements, and it will be understood that they will be duplicated at the opposite end of the side frame, that is, at both sides of the bolster window opening thereof. Also the opposite side frames of a car truck will have the corresponding improvements so that two brake beams may be guided.

The preferably hollow tension member 15 of the side frame has the bottom portion 16 below the bolster window opening and its inclined portion 17 which extends in the usual way to the usual journal boxes. The bolster guide column 18 extends upwardly from the tension member and the spring seat 19 extends inwardly of the side frame for supporting the spring for the bolster. All of these parts may be of the usual

construction, except for the present improvements.

Each side frame has a preferably integral guide flange or ledge 20 upon which the end of the brake beam 21 is supported at each side of the truck. Such guide flange 20 extends to or merges with the spring seat 18 and extends preferably at the angle of inclination described in aforesaid patents, and said flange extends along the tension member preferably in non-parallel relation to the inclined portion 17 thereof.

An inward shoulder or abutment 22 is located at a distance above the tension member proper and to that end it extends across the lower portion of the guide column 18 and along the upper edge of an upwardly projecting side member 23 which is in the form of a reinforcing web connecting with the upper portion of the inclined portion 17 of the tension member 15. Such shoulder or abutment 22 preferably extends parallel with the flange or ledge 20, and the member 23 is best integral with the column and tension member.

The extended surface or web 23 and shoulder 22 provide at the inner side of the tension member a preformed seat having an area sufficient to provide an inwardly facing base on which to mount a second flange or ledge 24 so that it will extend parallel with the flange 20, at a spaced distance above it. Such flange 24 provides a confining flange for the brake beam 21 when it is to be guided upon the side frame. In order to mount the flange 24 on the side frame it preferably has an upwardly extending base flange 25 fitted upon the preformed seat provided therefor by members 22 and 23. Hence the flange 24 and the base flange 25 are preferably formed from one piece of angle steel.

In order to detachably mount the beam confining flange 24 upon the tension member, bolts 26 may be used which pass through holes in the flange 25 and the base of the guide column, together with the web 23, nuts 27 being screwed onto the threaded ends of the bolts accessible to a workman through the window opening adjacent bolster opening 18. When the bolts or the fastenings have been tightened, the edge of flange 25 will abut the inner edge of the shoulder 22 and said flange and the confining flange 24 will be rigidly secured in position. Other fastening means may be employed, if desired, in order to rigidly mount the separately formed member 24, 25 on the side frame, and even rivets with upset ends may be employed. In the case of rivets it is obvious that the heads thereof may be readily cut off so that the rivets may be pushed out of the rivet holes, and the member 24, 25 removed.

By the provision of the beam supporting flange 20 and the beam confining flange 24 projecting inwardly from the side frame, a guiding recess 28 is provided for receiving the end of the brake beam, so that it may be guided substantially in accordance with aforesaid patents. It is preferred to strengthen and reinforce the lower end of the guide column 18 and the web 23 by means of brackets 29 cast integrally with the tension member. There is a suitable closure 30 formed at the upper end of the guide recess 28 to prevent the brake beam from falling out in that direction. Suitable cut-outs or recesses or notches 31, 32 are formed in the forward ends of the flanges 20, 24, as these are found desirable for allowing of proper lateral approach of the wheels to the side frame, as covered by said patents.

To provide for taking wear due to the move-

ment of the brake beam a suitable wear lining in the guiding recess 28 is provided, the same consisting of a plate of tempered steel or the like having a broad intermediate portion 33 to fit on the upper surface of the beam supporting flange 20, a down turned lip 34 to fit against the front edge of said flange and an upturned back member 35 to fit against the side frame, at the back of the recess 28, the upper edge of the back member 35 being tightly engaged by the beam confining flange 24 when that is mounted on the side frame. Rivets 36 are passed through the lining portion 33 and the flange 20, their ends being upset and countersunk in the said parts.

Referring to Figs. 1 and 4, should the occasion arise that the brake beam 21 and the brake heads, etc. thereon are to be removed from a truck, it is only necessary to detach from the side frames the separately formed beam confining flanges 24, and 10 when it is desired to again mount the beam for guidance on the side frames its ends are supported upon the supporting and guiding flanges 20 and the confining flanges 24 again secured 15 rigidly in position. Although the construction described is adapted for guiding the beams on the side frames, it will be seen that when the beam confining flanges are not in position on the side frames, as shown in Fig. 13, the beam may be 20 supported upon the usual hangers supported on the side frames, and then if the hangers should fail to support the beam, the beam will be prevented from falling to the track because it will 25 drop onto the flanges 20 at each side of the truck. Hence the construction shown and described is 30 of a dual type, that is, it may be used as a whole for guiding a beam along the side frames or in part to form a safety device to catch the beam in 35 case it drops. In the latter case, if because of the inclination of the beam supporting flanges 40 the beam should not come to rest thereon in the place just where it may have dropped, but would 45 gravitate inwardly down to the spring seats, as would probably be the usual case, the seats will catch the beam and prevent it from falling to the track. Then the beam can be removed upwardly 50 from between the side frames because the upper beam confining flanges are not in use and there are no inner surfaces integral with the side frames which would act to obstruct the raising of the beam, so that it can be removed through one 55 of the convenient openings of the truck.

In the modification illustrated in Figs. 7 to 12 inclusive the parts corresponding to the same parts illustrated in the other figures have corresponding reference numerals. In this construction the vertical web extension 38 from the bolster guiding column to the tension member is somewhat differently shaped from the web 23, and owing to the fact that it does not have the abutment shoulder 22 it does not extend so far 60 upwardly.

The angle metal member 39 above the beam supporting flange 20 is somewhat differently shaped from the corresponding member of the other figures. Such member 39 is provided with a beam confining flange 40 and a vertical base flange 41 which is somewhat cut away at 42 at the upper end of the incline of member 39.

A hinge knuckle 43 is formed on the upper end 70 of the guiding recess closure 30 and is preferably in line with the flange 40, which is formed with a double knuckle 44 to receive the knuckle 43. A hinge pin 45 passes through the adjacent inner wall of the tension member, and the same may 75 be passed through a hole in that wall by first en-

tering the pin upwardly through one of the holes 46 frequently formed in the bottom of a hollow or U-section tension member, and then the pin is passed through the knuckles 43, 44 and the ends riveted down to form a stationary pivot for member 39.

In this modification it will be seen that the angle member 39 may be swung upwardly on the pivot 45 so that the beam may be released upwardly, and the adjacent surfaces of the vertical base flange 41 and the web 38 are in frictional contact when the angle metal member 39 has been swung down to the position shown. One or more removable bolts 47 are preferably used to fasten the angle metal member 39 rigidly in using position, the bolts passing through the flange 41 and the web 38.

A wear plate of tempered steel is preferably employed in this modification, the same having an intermediate portion 48 to cover the beam supporting flange 20, a downwardly and inwardly bent front flange 49 and an upward back flange 50. Small downward teats or humps 51 are preferably formed on the intermediate portion 48, and when the wear plate is sprung onto the beam supporting flange 20, the said teats will take into depressions 52 in said flange, thereby mainly securing the wear plate in rigid position. To more securely hold the wear plate it is preferred that the back wall or flange 50 extend upwardly for such distance as to enter a small longitudinal recess 53 formed in the corner portion of the angle metal member 39, said member so acting after the same has been bolted or otherwise rigidly secured to the web 38 on the tension member.

It will be obvious to those skilled in the art that various changes may be made in the disclosed constructions without departing from the invention as defined in the appended claims.

What I claim as new is—

1. In a car truck, the combination of a side frame, a brake beam, a guide supporting the beam upon the inner side of the side frame and which is of a length to guide the beam during its range of travel, and a beam confining guide supported on said side, and which is substantially coextensive with and located above the supporting guide, the confining guide formed entirely separate from the side frame independently of the supporting guide, and provided with means to so support it on the said inner side of the frame movable away from the supporting guide as to render the beam removable upwardly.

2. A car truck side frame provided with a pair of guide flanges projecting inwardly therefrom and extending therealong and adapted to receive and guide the end of a brake beam between them, the lower flange in one piece with the frame and the upper flange a separately formed member having means for movably securing it directly to the frame for support therefrom so as to allow it to be moved to permit removal of the beam.

3. A car truck side frame, including a tension member, a bolster guide column, an upwardly projected side member connecting the column with the upper portion of the tension member and substantially in the plane of the inward side of the tension member, and a brake beam guide extending upon and along the inward side of said side member and movable with respect to the side member.

4. A car truck side frame, including a hollow tension member, a beam supporting guide extending along and in one piece with the inner

side of said member, a side member projected upwardly from and extending along said member substantially in the plane of the inner side of said member, and a beam confining guide extending along the inner side of the side member in opposed relation to the supporting guide, and movable to permit removal of the beam.

5. A car truck side frame having an upper lengthwise extending shoulder and a beam guiding supporting flange spaced below the shoulder, and the frame including a beam guiding confining flange held against the inner side of the frame and abutting the shoulder.

6. A car truck side frame provided at its inner side with a lateral supporting guide for the end of a brake beam, and a member of substantially right angular cross section throughout its length supported on said side above and parallel with the said guide, one flange thereof extending in a plane substantially parallel with and secured against said side and the other flange extending away from aforesaid flange and said side to guide and confine the end of the beam.

7. A car truck side frame provided with a pair of guide flanges extending therealong one above the other and adapted to receive and guide the end of a brake beam between them, and a removable fastening securing the upper flange directly to the frame whereby the upper flange is so secured as to permit removal of the beam upwardly.

8. A car truck side frame provided with a guide member extending along the inboard side of the frame and projecting inwardly from such side for guiding the end of a brake beam there along during normal brake operation, such member hingedly connected with the frame to permit removal of the beam, and means for fixing the member in stationary guiding position.

9. A car truck side frame provided with a guide member extending therealong for guiding the end of a brake beam during normal brake operation, a pivot transverse of the frame, whereby such member is hingedly connected with the frame to permit removal of the beam, and a removable fastening between the member and the frame for fixing the member in stationary guiding position.

10. A car truck side frame provided with a pair of guide flanges extending therealong one above the other and adapted to receive and guide the end of a brake beam between them, the upper flange hingedly mounted at one end on the frame, and means for fixing the upper flange in stationary guiding position.

11. A car truck side frame provided with a pair of guide flanges extending therealong one above the other and adapted to receive and guide the end of a brake beam between them, the upper flange movable away from the lower flange, and a wear plate protecting the lower flange and the inner edge portion of which plate is fixed between the upper flange and the frame.

12. A car truck side frame provided with a pair of guide flanges extending therealong one above the other and adapted to receive and guide the end of a brake beam between them, the upper flange movable away from the lower flange, and a wear plate protecting the lower flange and the inner edge portion of which plate is fixed between the upper flange and the frame, the outer edge portion of which plate is interengaged with the edge of the lower flange.

13. In a car truck, the combination of a side frame, a brake beam, and guiding means involving the terminal of the beam and opposed guides

arranged one over the other upon the inner side of the side frame for guiding said terminal of the beam laterally upon such inner side during brake operation, the upper one of the guides movable away from the other guide without disturbing the latter to permit either the removal of the beam from the truck or to adapt the beam for suspension from hangers.

14. A car truck side frame provided upon its inner side with a flange adapted to guide an end of a brake beam, and means for removably securing said flange by and of itself directly to the frame in guiding position, said flange being movable as a unit relatively to the beam end and the frame to permit removal of the beam when the securing means are out of action.

15. A car truck, including a side frame, a flange on the inner side of said frame and extending along it below the range of movement of a brake beam and adapted to support the end of the beam, said frame having a preformed area on its inner side constituting a seat spaced above and substantially the same length as said flange, and such seat being adapted to accept and furnish a support for a flange complementary to aforesaid flange.

16. A car truck, including a side frame having a tension member, a flange on the inner side of the tension member and extending therealong below the range of movement of a brake beam and adapted to support the end of the beam, the tension member having a member extending upwardly therefrom provided with a preformed area at its inner side constituting a seat spaced above and substantially the length of said flange, and such seat being adapted to accept and furnish a support for a flange complementary to aforesaid flange.

17. A trussed truck side frame, including a downwardly inclined tension member and a bolster guiding column extending down to the lower portion of the tension member, a web in substantially the vertical plane of the inward side of the frame and located in between the tension member and guide column, said web extending from the base of the column and extending along the upper surface of the tension member for a distance sufficient to provide an inwardly facing seat of substantial area adapted for the mounting of a detachable beam guiding flange thereon.

18. A car truck side frame provided with a pair of guide flanges extending therealong one above the other and adapted to receive and guide the end of a brake beam in the recess between them, a wear plate having a bottom portion and an upwardly-extending back flange in the back of the recess, and means rigidly securing the bottom portion of the plate to the upper surface of the lower flange, the upper edge-portion of said back flange engaged with and held by that portion of the upper flange which is nearest the side frame.

19. A car truck side frame provided with a pair of guide flanges extending therealong, one above

the other and adapted to receive and guide the end of a brake beam in the recess between them, a wear plate, and means rigidly securing the plate to the upper surface of the lower flange, the wear plate engaging and held by that portion of the upper flange which is nearest the side frame, and a removable fastening securing the upper flange to the frame whereby the upper flange is so secured as to permit removal of the beam upwardly and to permit access to the wear plate for renewing it, such upper flange engaging the wear plate when said upper flange is in guiding position.

20. A side member for a railway car truck, having lengthwise thereof substantially parallel flanges projecting inwardly from the side member, one over the other, providing a recess therebetween for guiding one end of a brake beam, the upper flange constituting an element formed for attachment to the side member and having a lateral surface adapted to bear on the adjoining lateral surface of the side member, and means for rigidly and removably attaching the upper flange to said member, with said surfaces mutually contacting the marginal edges of the said flanges extending along between the mutually facing surfaces of the side member and the brake head on that end of the beam, and said edges spaced a slight distance from said head, the removal of the upper flange from between the side member and head permitting removal of the beam from the lower flange.

21. A car truck side frame provided with a pair of guides extending therealong one above the other and adapted to receive and guide the end of a brake beam between them, one of the guides swingably mounted on the frame, and means for fixing the swingable guide in stationary guiding position.

22. A railway truck, comprising a side frame, having a window opening, a brake beam, and a device for guiding the beam including a bracket-member mounted on the frame adjacent the end of the beam and extending inwardly from the frame and shiftable on its mounting into and out of functioning position, and a detachable element for securing the bracket-member in place, said element being accessible through said opening to a workman at the outer side of said side frame.

23. A railway truck, comprising a side frame, a brake beam extending transversely of the truck and having an end-portion projecting in close proximity to the planes of the opposing faces of the frame, a member mounted on the frame and movable thereon, without being disassembled therefrom, into and out of a functioning position in which it provides a guide for the normal travel of said beam end-portion when the beam is operated in applying and releasing the brake, and readily detachable means for holding said member in position.

CHARLES R. BUSCH.
